R. J. HAUL

GARMENT HANGER

Filed May 31, 1924

Levinston:
ROBERT J. HAUL.
By John H. Brumaga
Attorney.

UNITED STATES PATENT OFFICE.

ROBERT J. HAUL, OF ST. LOUIS, MISSOURI.

GARMENT HANGER.

Application filed May 31, 1924. Serial No. 716,987.

This invention pertains to garment hangers or racks.

One of the objects of this invention is to provide a rack for garments which may be mounted on a wall and arranged to be extended or collapsed and so as to be retained in extended or collapsed position.

Another object is to provide such a garment rack with a stop to prevent its being extended beyond the safe limit.

Another object is to provide improved means for preventing sagging of the rack.

Another object is to provide means whereby the weight of the articles hung on the rack will tend to return the same to retracted position.

Further objects will appear from the following description in connection with the accompanying drawing, in which—

20 Figure 1 is a side view of a garment rack embodying this invention and shown in extended position; and

Figure 2 is a similar view showing the rack in retracted or collapsed position.

25 In accordance with this invention, a garment rack is provided which comprises an ordinary lazy tongs built up of diagonal members 1 and 2 pivoted together at their ends and also at their middle portions in the usual well known manner. These lazy tongs are mounted on a support 3 adapted for attachment to the wall. The connection is made by a pair of connecting elements or links 4 pivoted to the ends of the members 1 and 2 and also pivoted at 5 to the support 3. These elements extend beyond their pivots 5 and have their ends formed to provide

abutment surfaces 6 adapted to engage the wall flange 7 of the support 3. When the lazy tongs are drawn out to extended position, the members 4 turn about their pivots 5 until their abutments 6 engage the flange 7 of the support. When in this position, further movement of the lazy-tongs is pre-

40 vented by the rigidity of the members 4. This rigidity also prevents the sagging of the rack under the weight of its load. The outer end of the lazy tongs has pivoted thereto by means of a pair of links 8 a handle 9 by means of which the same may be manipulated.

The members 1 which extend downwardly and outwardly from the wall have extensions 10 beyond their lower pivots which are provided at their ends with hooks or other suspension means 11. When the rack is in extended position, the weight of the load hung on any of the hooks 11 tends to force the lower ends of the members 1 downwardly thereby producing a leverage which tends to retract or close the lazy tongs. This construction therefore provides that so long as articles are suspended from the hooks 11, the rack will tend to close itself unless restrained. Pivoted at 12 to the support 3 is 55 a retaining member or link 13 provided with notches 14 adapted to engage the headed pin 15 which forms the pivot of the last pair of members 1 and 2. When the rack is extended, the link 13 may have its outer notch 14 engaged with the pin 15 so as to retain the rack in extended position. When in retracted position, the inner notch 14 may be engaged with said pin to retain the rack in collapsed position. 75

It will be seen therefore that in accordance with this invention, a simple garment rack is provided which is economical of manufacture and which will be reliable in service. The members 4 provide stops to 80 prevent abuse of the rack by drawing it out too far and at the same time prevent sagging of the same. The extensions 10 provide that when loaded the rack will automatically tend to return to retracted position. The 85 latch 13 may, however, be used to retain the rack in either extended or collapsed position.

It is obvious that various changes may be made in the details of construction without departing from the spirit of this invention; it is therefore to be understood that this invention is not to be limited to the specific details shown and described.

Having thus described the invention, what 95 is claimed is:

1. A garment rack, comprising, a support adapted for mounting on a wall, and a lazy-tongs having pivotal connections with said support, certain members of said lazy-tongs being extended beyond others and provided with suspension means, whereby the weight 100

of the suspended articles tends to retract said lazy-tongs.

2. A garment rack, comprising, a support adapted for mounting on a wall, and a lazy-
5 tongs having pivotal connections with said support, certain members of said lazy-tongs being extended beyond others and away

from said support and provided with suspension means, whereby the weight of the suspended articles tends to retract said lazy-¹⁰ tongs.

In testimony whereof I affix my signature this 12th day of May, 1924.

ROBERT J. HAUL.
